COIN PURSE

Nels H. Swanson, Chicago, Ill.

Application April 25, 1938, Serial No. 203,989

6 Claims. (Cl. 150—37)

The present invention relates to coin purses and more particularly to a "zipper" type of casing having bill, coin, and card pockets provided therein, with one of the pockets provided with an extension to which the lower bevelled end of a coin holder, of a molded plastic product, is secured and formed with suitable coin slots and with inclined top faces to expose coin rest surfaces and guides to facilitate convenient insertion of coins and the easy extraction of the same past suitable detent members provided in the coin slots.

It is an object of this invention to provide a "zipper" type of coin case provided with a coin holder constructed of a molded plastic, such as a cellulose acetate product.

It is also an object of this invention to provide a coin case constructed of leather or other suitable material forming a front and a back adapted to have the major portions of the margins thereof connected by means of a "zipper" mechanism to enclose a hingedly supported coin holder preferably constructed out of a molded plastic formed with coin slots of different sizes, with the inner ends of the coin slots suitably inclined or bevelled and with the outer ends of the coin slot partitions suitably inclined to expose the outer end portions of the partition rear flanges to facilitate the insertion of coins into the slots, said inclined outer ends of the partitions serving as guides for the thumb of a person's hand when coins are either inserted or withdrawn from the coin holder.

It is a further object of this invention to provide a "zipper" type coin case wherein a slotted coin holder is preferably constructed of a cellulose acetate product, the inherent properties of which lend themselves admirably to the formation of suitable coin slots including stop means for retaining the coins in the respective slots and at the same time permitting coins to be moved past the same by manual force when coins are either inserted or removed.

It is an important object of this invention to provide an improved type of coin case of a middle hinge type provided with a marginal zipper closure mechanism for enclosing a slotted coin holder, the lower end of which is hingedly supported within the casing, with said coin holder being preferably constructed of a molded plastic such as a cellulose acetate product, permitting the partitions separating the coin slots to be suitably bevelled or inclined for the convenient inserting of coins and the removal of coins from the slots which are open both at the front and the back

of the coin holder to serve as finger guides for the movement of coins past detents or retaining clips provided near the outer ends of the coin slots to obviate the accidental sliding of coins out of the slots, but permitting the movement of coins past the same when the coins are manually moved.

Other and further important objects of this invention will be apparent from the disclosures in the specification and the accompanying drawing.

The invention (in a preferred form) is illustrated in the drawing and hereinafter more fully described.

On the drawing:

Figure 1 is a plan view of the coin case in complete open position and showing the coin holder lying flat against one of the inner pockets forming part of the coin case.

Figure 2 is an enlarged fragmentary detailed section taken on line II—II of Figure 1, and showing a coin in position in the lower end of the coin slot.

Figure 3 is a fragmentary top end view of the coin holder.

Figure 4 is a fragmentary detail section taken on line IV—IV of Figure 2 through one of the coin holder partitions and illustrating one form of a coin stop.

Figure 5 is a fragmentary detail transverse section taken through a coin holder partition and illustrating a modified form of spring clip coin stop.

Figure 6 is a fragmentary section through the hinge portion of a different form of coin purse illustrating a modified form of hinge mounting for the coin holder, with the purse open to permit the cover sections to serve as receivers for coins removed from the holder or accidentally dropped during removal.

As shown on the drawing:

The improved coin purse embodies a combination casing and coin holder. The casing is adapted to be constructed out of leather or other suitable material formed to provide a pair of covers or a back and a front section both of identical form and integrally connected by means of a middle transverse hinge portion 1. Each of the cover sections is constructed of two layers of material consisting of an outer layer of leather 2 or other suitable material and a soft leather lining 3. The body of the coin casing at the end of the hinge section 1 is recessed or notched as at 4.

For the purpose of closing the coin case the

marginal edges of the two cover sections have secured thereto the mounting tapes 5 of "zipper" strips 6. Coacting with the "zipper" strips 6 of the two cover sections of the casing is a latching slide 7 provided with an actuating tab 8.

When it is desired to close the purse case, the two cover sections are swung towards one another on the hinge connection 1 and the "zipper" tab 8 is then engaged to pull the latch 7 over the 10 "zipper" strips 6 of the two cover sections to completely close and lock the coin purse.

Secured in one of the cover sections is a key, coin, and bill pocket 9. Secured on the inner face of the other cover section is a second bill and 15 card pocket 10. Both the pockets 9 and 10 have the pocket openings directed outwardly or away from the hinge portion 1, so that the pockets are readily accessible when the coin purse is open without any interference by the coin holder hereinafter described.

Integrally formed on the bottom longitudinal margin of the pocket 10 is an extension forming a hinge flap or strip 11.

A denominational coin holder is mounted with- 25 in the purse between the cover sections and is attached to the hinge member 11 to permit the coin holder to be hingedly swung back and forth between the coin purse cover sections when the purse is open so that access may be had to either one or both of the pockets 9 and 10.

The purse is provided with an improved type of coin holder which is in the form of a block or board member which may be formed out of various kinds of material but preferably is constructed of a molded plastic such as a cellulose acetate product known as "Tenite", or the board may be constructed of a phenolic condensation product. The coin holder is shaped to be enclosed between the cover sections of the purse, and consists of a block or board 12 having a bevelled or inclined bottom surface 13 and a bevelled or inclined top surface 14. In the form of the purse illustrated in Figure 2, the lower inclined face 13 of the coin holder is placed in contact with the top surface of the hinge strip 11 and is rigidly secured thereto by means of rivets 15 or other suitable fastening means. In the form of the coin purse illustrated in Figure 6, the lower inclined surface 13 of the coin holder 12 is fastened to the top face of the hinge strip 11 providing an arrangement affording a greater leeway of movement of the hinged coin holder.

With the coin holder hingedly supported in the purse between the cover sections, it will be noted that when the coin purse is open that the cover sections act as receivers or pockets for receiving coins withdrawn from the holder or coins which are accidentally dropped while being removed from the holder.

The holder 12 is molded or shaped to provide a plurality of adjacently positioned coin pockets of different sizes for receiving coins of different denominations, such as pennies, nickels, dimes, and quarters. As clearly illustrated in Figures 1 and 3, the coin pockets, which are represented as a whole by the reference numeral 16, are separated from one another by slightly flexible uprights or partitions 17 formed with coin guide grooves 18 which extend upwardly from inclined bottoms 19 in the coin pockets upwardly to the top inclined face 14 at the top of the coin holder. The inclined ends of the partitions expose parts of the inner faces of the partition back flanges so that said exposed back flange parts form coin rests and guides to facilitate the insertion of coins into

the coin pockets. As noted in Figure 1, the two outermost uprights or partitions 17 have coin guide grooves 18 on the inner sides thereof only, the outer sides being plain and forming the ends of the coin holder. Each of the coin pockets 16 is provided on the front side of the holder with a thumb slot 20, which extends upwardly from substantially the lower end of the inclined bottom 19 of the coin pocket to the upper end of the coin holder. Each of the coin pockets is also provided with a finger slot 21 which, in the form illustrated in Figure 1, extends downwardly from the top rear edge of the coin holder to a short distance below the top inclined surface 14 of the coin holder. While the finger slots 21 are illustrated and described as being shallow or short, they may, of course, be elongated to extend from the top of the coin holder to the upper edges of the inclined bottoms 19 of the coin pockets.

Integrally formed in one of the grooves 18 of each of the coin pockets near the outer or upper ends of the pockets is a coin stop or detent 22, as clearly illustrated in Figures 2 and 4, to serve as an obstruction for coins 23 when the coins are either inserted into the holder or removed therefrom. As a coin, which is gripped between the thumb and a finger of a person's hand, is manually pulled or pushed past the stop or detent 22, the mouth or open end of the coin pocket is temporarily expanded to permit passage of the coin.

By providing each of the coin pockets with a long thumb slot and with a short finger slot, a coin within a coin pocket may first be engaged by a thumb and pushed outwardly until it contacts the stop or detent 22, in which position the coin may be gripped between the thumb and a finger and then readily pulled past the stop or detent by expanding the mouth end of the coin pocket which is permitted by the resilient or flexible features inherent in the coin pocket parti- 40

tions 17.

Figure 5 illustrates a fragmentary portion of a modified form of coin holder which is substantially the same as that hereinbefore described, with the exception that the partitions indicated by the reference numeral 24 are provided with a notch or opening 25 near the upper end thereof into which a double spring stop or detent 26 is inserted. The double stop or detent 26 is of U-shaped construction, both arms of which are provided with rounded spring-like portions which serve as the coin stops or detents and project into the coin pockets into the paths of travel of the coins as they are removed from the coin holder or are inserted into the coin holder.

The pocket 9 in one of the cover sections opens out outwardly away from the hinge connection between the cover sections, and if desired, the pocket 9 may be sewed transversely as at 27 to provide a plurality of smaller pockets of a size sufficient to receive large coins such as dollars and half dollars. If desired, the large coin pockets may be used for carrying flat keys, clothes checks, or the like.

It will, of course, be understood that numerous details of construction may be varied through a wide range without departing from the principles of this invention, and it is therefore not the purpose to limit the patent granted hereon otherwise than necessitated by the scope of the appended 70 claims.

I claim as my invention:

1. A coin purse comprising a casing, means for holding the casing closed, a flexible hinge flap secured in the casing, and a denominational coin

holder secured to the hinge flap, said holder having inclined bottoms and tops, and also being provided with a plurality of adjacently positioned coin slots of different sizes for coins of different 5 denomination and with coin guide grooves formed with detents near the outer ends thereof for retaining coins within the coin holder, said inclined bottoms positioning the coins in inclined overlapping relationship and said inclined tops 10 providing coin rests in the holder to facilitate the insertion of coins therein.

2. A coin purse comprising hingedly connected 15 cover sections, means for holding the purse closed, a combination pocket and hinge member in the purse, and a coin holder secured to the hinge member to permit the coin holder to swing into different positions with respect to the cover sections, said coin holder comprising a board having inclined top and bottom surfaces with the inclined 20 bottom surface secured to the hinge member, said board also having a plurality of coin receiving pockets of different sizes for coins of different denominations, said pockets being formed with inclined bottoms and with side coin guide grooves 25 having coin stops therein adapted to be flexed by the coins in the insertion of coins into the coin pockets and when coins are removed therefrom.

3. A coin purse comprising a pair of hingedly connected cover sections, a hinge member enclosed thereby, and a coin holder secured to the hinge member between the cover sections, said coin holder comprising a molded plastic boardlike member having bottom and top inclined faces and provided with a plurality of spaced coin pockets 35 of different sizes, said inclined bottom faces holding the coins inclined and overlapping one another within the holder and said inclined top faces affording a thumb slide for the easy extraction of coins, and coin rests for the insertion of 40 coins, said pockets each having coin guide grooves therein, coin stops in the grooves adjacent the outer ends of the coin pockets to cause expanding of the outer ends of the pockets when the coins are inserted or removed, each of said coin pockets 45 formed with an inclined bottom and with a front thumb slot extending from the lower end of the inclined bottom to the top of the coin holder and with a shallow back finger slot permitting the

coin engaged by the thumb through the thumb slot to be moved outwardly in a coin pocket into contact with coin stops and adjacent the finger slots to permit the coin to be clamped between the thumb and a finger to be pulled past the coin 5 stops and out of the holder.

4. A coin purse comprising a pair of cover sections having a hinge connection therebetween, a pocket secured on the inner side of one of the cover sections, a hinge extension integrally 10 formed on the bottom of the pocket, a coin holder having an inclined bottom secured to the hinge extension to permit pivotal swinging of the coin holder with respect to said cover sections, said coin holder having a plurality of coin pockets of 15 different sizes provided therein having inclined bottoms and separated by resilient grooved partitions for receiving therebetween small coins of different denominations and sizes, and stop members in the grooved partitions for governing the 20 insertion and removal of coins from the coin holder.

5. A purse comprising a pair of cover sections connected together by a hinge section disposed 25 between them, a member secured to one of said cover sections to define a pocket therewith having a closed end adjacent the hinge section and said member extending beyond said closed end to define a hinge member, a coin holder comprising a substantially rigid member having an inclined 30 lower portion attached to said hinge member for swinging movement between said cover sections.

6. A coin purse comprising a cover section, a combination pocket and hinge member in the 35 purse, and a coin holder secured to the hinge member to permit the coin holder to swing into different positions with respect to the cover section, said coin holder comprising a coin receiving member having an inclined bottom surface secured to the hinge member, said coin receiving 40 member also having a plurality of coin receiving pockets formed with inclined bottoms and with side coin guide grooves having coin stops therein adapted to be flexed by the insertion of coins into the pockets and by the removal of coins from said 45 pockets.

NELS H. SWANSON.
